WATER INLET FITTING

Eugene L. Kilbourn, Marshall, Mich., assignor to Progressive Dynamics, Inc., Marshall, Mich.

Filed Dec. 13, 1965, Ser. No. 166

Term of patent 7 years

(Cl. D91—1)

FIG. 1 is a front elevational view of a water inlet fitting embodying my new design,

FIG. 2 is a side elevational view of my new design as taken from the left of FIG. 1, the opposite side having a corresponding appearance,

FIG. 3 is a top plan view of the fitting of FIG. 1,

FIG. 4 is a rear elevational view, and

FIG. 5 is a bottom view of the water inlet fitting of my new design.

The dominant features of my design reside in the portions shown in full lines.

I claim:

The ornamental design for a water inlet fitting, as shown and described.
